DESIGN FOR A HAIR WAVE CLIP

William Huppert, New York, N. Y., assignor to Delamere Company, Inc., a corporation of Delaware

Application May 25, 1945, Serial No. 119,726

Term of patent 14 years

(Cl. D86—10)

To all whom it may concern:

Be it known that I, William Huppert, a citizen of the United States and resident of New York city, in the county of New York and State of New York, have invented a new, original, and ornamental Design for a Hair Wave Clip, of which the following is a specification, reference being had to the accompanying drawing, forming part hereof, in which—

Figure 1 is a side view of a hair wave clip
showing my new design;

Fig. 2 is an end view thereof;

Fig. 3 is a top plan view; and

Fig. 4 is a bottom plan view.

I claim:

The ornamental design for a hair wave clip,
substantially as shown.

WILLIAM HUPPERT.
